[57] CLAIM

The ornamental design for an end cap for furniture slats, substantially as shown and described.

DESCRIPTION

FIG. 1 is a perspective view of one end of the end cap showing the recessed side having recesses for housing the ends of the slats, the other end being broken away; FIG. 2 is a similar view of the one end of the end cap shown in FIG. 1 showing the opposite plain side of the end cap;

FIG. 3 is a side elevation of the plain side of the end cap with a central portion broken away;

FIG. 4 is a plan view of the end cap with the central portion broken away;

FIG. 5 is a view in elevation of the recessed side of the end cap with a central portion broken away; and

FIG. 6 is an end elevation.
The end cap is broken away in the figures to indicate indeterminate length.
